UNITED STATES PATENT OFFICE.

ERNEST G. CLARK, OF DE KALB, ILLINOIS, ASSIGNOR TO MELVILLE CLARK PIANO COMPANY, OF CHICAGO, ILLINOIS, A CORPORATION OF ILLINOIS.

PAPER-FEED FOR PERFORATING-MACHINES.

1,108,338.

Specification of Letters Patent. Patented Aug. 25, 1914.

Application filed January 2, 1914. Serial No. 809,845.

To all whom it may concern:

Be it known that I, ERNEST G. CLARK, a citizen of the United States, residing at De Kalb, in the county of Dekalb and State of Illinois, have invented new and useful Improvements in Paper-Feeds for Perforating-Machines, of which the following is a specification, reference being had to the accompanying drawings, forming a part thereof.

10 The purpose of this invention is to provide an improved mechanism for drawing webs of paper through a machine in which the same is perforated for such purposes as note sheets or automatic controller sheets for 15 pneumatically and electrically operated mechanisms.

It consists in the elements and features of construction shown and described as indicated in the claims.

20 In the drawings:—Figure 1 is a top plan view of the delivery platform of a perforating machine equipped with this invention. Fig. 2 is a section at the line 2—2 on Fig. 1. Fig. 3 is a detail section on a much 25 enlarged scale at the line 3—3 on Fig. 2. Fig. 4 is a section at the line 4—4 on Fig. 3 showing in plan view the paper-grip operating cams. Fig. 5 is a view similar to Fig. 4 showing the grip releasing cams.

30 The webs of paper to be perforated in a machine of the character for which this invention is designed are customarily led to the perforating machine from spools, as many as the number of sheets to be perforated 35 at once, usually about fifteen; and having passed through the machine, the entire fifteen sheets superposed are engaged as a solid blanket, and operated upon bodily to draw them all together through the perforating machine, with the short step-by-step action necessary for the proper operation of 40 the perforating machine. Only the delivery platform of the perforating machine is shown in the drawings, the preceding parts 45 of the mechanism having no specific relation to the features of this invention.

In the drawings, the delivery platform is represented as a skeleton table, 1, supported by suitable legs, 2, having journaled underneath it at the receiving end the shaft, 3, of the ratchet wheel, 4, and sprocket wheels, 5, 5, for driving the feed chains, 6, 6, and at the opposite or delivery end, the shaft, 7, of the idler sprocket wheels, 8, 8, for the 55 said chains.

9 is a feed pawl and 10 is a detent pawl engaging the ratchet wheel, 4, to give the necessary step feed movement to the chains. The feed pawl, 9, may be operated in any convenient manner not shown for giving it 60 the proper reciprocation to actuate the ratchet wheel and its shaft. The skeleton table, 1, comprises cross plates, 12 and 13, respectively, near the receiving and delivery ends for supporting the cams which operate 65 the paper gripping devices. These gripping devices will first be described. They consist each of a bar, 14, connecting the opposite links of the chains, 6, 6, being mounted upon the outer side of the links so as to 70 pass freely around the sprocket wheels which drive and carry the chains, and so as to travel above the table, 1, whose upper surface,—that is, the surface of the plates, 12,—is in a plane a little below the path of travel 75 of the inner or under side of the bar as it is carried from receiving to delivery end by the travel of the chains. Immediately outside the paths of the upper or operating 80 ply of the chains, there are mounted upon the table track bars, 15, 15, upon whose upper edges the ends of the gripper bars, 14, ride and are guided in their passage from receiving to delivery end of the table, and to 85 retain the gripper bars accurately in their path of travel,—that is, prevent them from oscillating endwise as they move over the length of the table,—angle bars, 16, 16, are mounted upon the margin of the table immediately outside the track bars, 15, the 90 vertical flange of the angle bars extending up beyond the upper edge of the track bars so as to afford stops for the ends of the gripper bars, 14.

Upon the gripper bar near each end but 95 inside the point of attachment of the bar to the chain, there is mounted a gripper which consists of a short rectangular sleeve, 17, encompassing the bar, having pivoted in it above the bar a gripping jaw, 18, which extends inward from its pivot overhanging the bar at a distance above the same sufficient to admit the maximum thickness of the blanket of paper sheets to be gripped, and having its inner end beveled or rounded 100 on the under side to adapt it to ride up easily on to the edge of the blanket. A spring, 19, is provided reacting between the jaw, 18, and the bar, 14, to normally hold the jaw open; that is, to hold its inner end up from the 110

bar, as seen in full line in Fig. 3. The spring, 19, is free from attachment to the bar so that it does not interfere with the sliding of the sleeve and jaw on the bar, as hereinafter explained. To the sleeve, 17, under the gripper bar there is attached a lever arm, 20, which extends along under the bar inward from the sleeve. This lever has its inner end portion, 20^a, deflected upward 10 toward the bar, and its inner extremity beveled at 20^b, to adapt it for encounter with and actuation by a cam, 21, which is mounted on the under side of the bar and adapted to slide thereon from a position at which its 15 sloping end, 21^a, is a very short distance from the beveled end, 20^b, of the lever, 20, when the sleeve, 17, is at its outermost position shown in Fig. 3, to a position substantially as far removed inward from that position 20 as the amount of movement which it is desired to give the sleeve, 17, in order to advance the jaw, 18, from its full line position shown in Fig. 3, outside the margin of the blanket, A, of paper sheets to its position 25 shown in dotted line in said Fig. 3 where it overhangs and grips the blanket. For thus sliding on the bar, the cam, 21, is provided with side wings, 21^b, having inturned lips 21^c, which engage longitudinal grooves, 30 14^b, in the lateral edges of the bar, 14. Upon the under side of the sleeve, 17, it is provided with a stud-and-roll abutment, 24, which is positioned so as to encounter the sloping edge, 25^a, of a cam, 25, mounted on 35 the cross plate, 12, near the receiving end of the table. When in the travel of the chain the abutment, 24, encounters the cam edge, 25^a, the sleeve, 17, is crowded inward along the bar, 14, a distance equal to the 40 dimension of the cam, 25, transversely of the line of travel, which is a sufficient distance to bring the jaw, 18, to a position overhanging the margin of the paper blanket, as seen in dotted line in Fig. 3. The inward thrust 45 of the cam is limited by a stud, 28, which projects from the under side of the bar, 14, and stops the lever, 20, at the end of a slot or notch, 20^c, in the end of said lever. Upon the cross plate, 12, there is mounted a second cam, 26, having a sloping edge, 26^a, positioned in the path of a stud-and-roll abutment, 27, which projects from the under 50 side of the cam, 21, in position to be encountered by said abutment substantially at 55 the instant at which the abutment, 24, having passed off the sloping edge, 25^a, of the cam, 25, stands in the position shown in dotted line in Fig. 4; that is, immediately after the jaw, 18, has been thrust inward so 60 as to overhang to the full extent desired the margin of the blanket, A. The travel of the chain continuing from this point, the cam, 26, by its sloping edge, 26^a, crowds the cam, 21, outward—that is, toward the sleeve, 65 17,—and its sloping edge, 21^a, encountering

the beveled edge, 21^b, of the lever, 20, crowds the inner end of said lever down, rocking the sleeve, 17, on the bar so as to bring the jaw, 18, down tightly upon the paper blanket whose margin it overhangs. The 70 outward thrust of the cam, 26, upon the cam, 21, is limited by the same pin, 28, which stops the inward thrust of the lever, 20, the outer end of the cam, 21, being provided with a notch, 21^c, the bottom of which encounters 75 the pin at the proper limit of outward thrust of the cam, 21.

The process above described is performed at both margins of the paper blanket, the gripping devices described being duplicated 80 on the two ends of the bar, 14, and the paper blanket is thereby simultaneously gripped and held at opposite marginal points and carried by the chains as they travel outward over the table. A sufficient number of bars, 85 14, with gripping devices as described are provided to insure the paper being held without slippage. As illustrated, in the entire circuit of the chains there are fourteen such bars with the grippers upon the opposite end portions of each. The blanket having been thus gripped at the receiving end 90 of the table is held by the grippers until they successively approach the delivery end where the table has upon the cross plate, 13, 95 cams, 29 and 30, positioned for reversing the movements which have been performed by the cams, 25 and 26, as the grippers passed over the plate, 12. The cam, 29, has a sloping edge, 29^a, positioned for encounter 100 of the abutment, 27, traveling in the path indicated by the dotted line position in Fig. 3, the deflection of said edge being in direction to force the abutment outward as the work travels, moving it back to its position 105 on the bar shown in full line on Fig. 3, its position with respect to the cam being shown in dotted line in Fig. 5. This action, it will be observed, withdrawing the cam, 21, from the lever, 20, releases the grip of the jaw, 18, upon the paper blanket. Substantially 110 at the instant at which this is effected by the abutment, 27, reaching the dotted line position shown in Fig. 5, the abutment, 24, encounters the sloping edge, 30^a, of the cam, 30, and is by it deflected outward, causing 115 the sleeve, 17, to withdraw the jaw, 18, to the position shown in full line in Fig. 3, clearing it from the paper blanket, which is thereby left free to be delivered beyond the 120 delivery end of the table.

I claim:—

1. In a web-feeding mechanism, in combination with a table onto which the web is delivered; bars extending transversely of the table, and means for propelling them transversely in an endless path comprising courses longitudinal of the table above and below the same; web-clamping grippers mounted on the bars, movable thereon to po- 130

sitions outside of the lane in which the web is delivered; cam-encountering abutments on the grippers; cams on the table positioned for encounter with the abutments after the bars have entered upon their upper course over the table, and adapted by such encounter to move the grippers inward to cause their jaws to overhang the margins of the web; means for clamping the grippers on the web and additional cams on the table positioned for encounter with the clamping means to clamp the grippers after they have been moved inward by the first mentioned cams; both said sets of cams being near the entering end of the table, and additional cams near the delivery end of the table positioned for first releasing the clamping devices and afterward withdrawing the movable grippers.

2. In a web-feeding mechanism, in combination with the table, the endless belts and the transverse bars connecting the belts; grippers mounted for rocking and sliding on the bars, comprising each a jaw above the bar projecting inward for overhanging the path of the web, a lever below the bar projecting inward there-along, and a spring reacting between the gripper and the bar to normally hold the jaw and the lever elevated at their inner ends; a cam mounted movably on the bar for encounter with the inner end of the lever to wedge it downward; cam-encountering abutments on the gripper and cam, and cams on the table positioned for encounter of said abutments successively as the bar travels along the table from the entering end, said cams being adapted respectively to move the gripper inward to cause its jaws to overhang the web, and to move the cam on the bar outward to clamp the jaw onto the web.

3. In a paper feeding mechanism, in combination with the table, the parallel endless

belts and their carrying and operating and driving wheels, respectively, mounted on the table for travel of a ply of each belt longitudinally there-above from receiving to delivering end; bars connecting the belts; a web-engaging gripper mounted on each bar, comprising a jaw adapted to overhang the margin of the web and a lever under the bar for clamping the jaw onto the web; a cam movable on the bar for operating the lever; means for moving the grippers inward for moving the cam on the bar for clamping; cams on the table near the delivery end, positioned for encountering the lever-operating cam and the gripper respectively, to first give the cam its lever-releasing movement and afterward move the gripper outward to carry its jaw off the margin of the web.

4. In a web-feeding mechanism, in combination with a table onto which the web is delivered longitudinally; bars transverse to the table; means for moving them laterally in an endless path comprising courses longitudinal of the table above and below the same; means carried by the bars for clamping the margins of the web, and cams on the table adapted for operating said clamping devices by the movement of the bars longitudinally of the table at the entering and delivering ends thereof, the table having longitudinally-extending up-standing ribs for resisting the tendency of the cams to crowd the rods endwise in operating the clamping devices.

In testimony whereof, I have hereunto set my hand at De Kalb, Ill., this 27 day of Dec., 1913.

ERNEST G. CLARK.
